UNITED STATES PATENT OFFICE.

WILLIAM M. LESTER, OF SPRINGFIELD, MASSACHUSETTS.

METHOD OF INDEXING BOOKS.

SPECIFICATION forming part of Letters Patent No. 404,294, dated May 28, 1889.

Application filed January 26, 1889. Serial No. 297,673. (No model.)

To all whom it may concern:

Be it known that I, WILLIAM M. LESTER, a citizen of the United States of America, residing at Springfield, in the county of Hampden and State of Massachusetts, have invented 5 new and useful Improvements in Methods of Indexing Books, of which the following is a specification.

This invention relates to a new and improved method of indexing books, the object 10 thereof being to enable a most ready and speedy finding of the subject-matter therein contained; and the invention consists, essentially, in delineating or otherwise indicating 15 on the edges of the leaves marks or plain figures or forms having widths corresponding to the combined widths of a number of leaves embracing a given subject-matter of the book, whereby the position of the subject-matter is 20 indicated without opening the book.

The invention further consists in subdividing the above-mentioned figures or forms, whereby the positions in the book of subdivisions of the subject-matters may be readily 25 ascertained; and the invention still further consists in indicating by symbols marked on the edge of the book on or near to said configurations and subdivisions thereof, to identify or determine to which subject-matter or 30 subdivision thereof the configuration or its subdivision relates.

In the drawings the method of indexing books in accordance with this invention is 35 illustrated, and Figure 1 is a perspective view of the edge portion of a book having an index of its subject-matter marked on its edge. Fig. 2 is a diagram view, to be hereinafter referred to. Fig. 3 is a view in detail, to be hereinafter particularly referred to.

The index here particularly illustrated is 40 designed for and applied on a commercial-agency reference-book, and the rectangular configurations *a*, printed or stenciled on the edge *b* of the leaves, extend by their widths

45 across different divisions of the subject-matter thereof. For instance, all the leaves of the book comprised within the width of the particular square *x* are devoted to ratings of firms, &c., in the State of Connecticut, and by 50 the abbreviation "Conn." the particular

square is identified with regard to the subject-matter covered thereby. The rectangular or otherwise formed configurations are preferably to be arranged diagonally across the edge of the book, as shown in Fig. 1, in one 55 line, whose range from end to end of the book traverses the combined width of all the pages thereof.

Where the book is comparatively short, as in duodecimo volumes, and with a desirable 60 height for the indicating-rectangles, the length of the book would be occupied thereby before the width of the book had been traversed. The said configurations may be made in two or more diagonal lines, as seen in Fig. 2, one 65 thereof commencing at the top left-hand edge of the book-leaves and running to the bottom thereof at the center of their combined widths, including, say, subject-matters from A to M, and then commencing at the middle portion 70 and running to the lower right-hand part of the edge, including the remaining subject-matters of the book, and, again, the configurations may obviously be disposed in other arrangements. 75

The configuration covering a given division of subject-matter, to the end of indicating the position in the book of a subdivision thereof, may have a subdividing-mark, as the smaller rectangles, *d*, at its borders, covering 80 so much of its width as will correspond to the combined width of pages containing the subdivision of the subject-matter, and such rectangles may have words or other symbols placed on or near them, as seen at *f*, by which 85 to identify the subdividing index-marks. Thus while the rectangle proper, against which "N. Y." is placed, indicates that the pages covered thereby are all devoted to ratings for firms, &c., in the State of New York, the pages 90 covered by the rectangle embracing an intermediate portion of the width of said rectangle proper are devoted to ratings for New York city.

The employment of the improved index on 95 a commercial-agency reference-book is merely by way of illustration, the same being no more applicable to such books than others, and may be applied as well to directories, dictionaries, digests, &c. The indicating-con- 100

figurations may be applied in various ways on the edges of the leaves, as by stenciling or printing, and they may each be of a tint or solid color or may be formed in outline, and in some instances the identifying words or symbols may be placed within such outlines, and in Fig. 3 such latter form of index is shown, being applicable where few subject-matters are comprised in a book, it being possible, therefore, to make each configuration larger.

What I claim as my invention is—

1. The improved method of indexing books herein described, the same consisting in indicating by delineating or otherwise marking on the combined edges of the leaves configurations having widths corresponding to the combined widths of the leaves comprising the subject-matters of the book, substantially as described.

2. The improved method of indexing books herein described, the same consisting in indicating by delineating or otherwise marking

on the combined edges of the leaves configurations having widths corresponding to the combined widths of the leaves comprising the subject-matters of the books, and in marking symbols on the edges of the book on or near said configurations to identify the subject-matters, substantially as described. 30

3. The improved method of indexing books herein described, the same consisting in indicating by delineating or otherwise marking on the combined edges of the leaves configurations having widths corresponding to the combined widths of the leaves comprising the subject-matters of the book, and in indicating subdivisions of the widths of any or all of said configurations to determine the subdivisions of the subject-matters indicated thereby, substantially as and for the purpose described. 35 40

WILLIAM M. LESTER.
